UNITED STATES PATENT OFFICE.

ERNEST H. SCHMIDT, OF CLEVELAND, OHIO, ASSIGNOR TO THE NATIONAL MALLEABLE CASTINGS COMPANY, OF CLEVELAND, OHIO, A CORPORATION OF OHIO.

FRICITION DRAFT-RIGGING.

1,130,439.

Specification of Letters Patent.

Patented Mar. 2, 1915.

Application filed June 21, 1912. Serial No. 704,944.

To all whom it may concern:

Be it known that I, ERNEST H. SCHMIDT, a citizen of the United States, and a resident of Cleveland, Cuyahoga county, Ohio, have invented new and useful Improvements in Friction Draft-Rigging, of which the following is a specification, reference being had to the accompanying drawings, in which—

10 Figure 1 is a plan view partly in section showing my device applied to the framing of a car; Fig. 2 is a section on lines II—II of Fig. 1; Fig. 3 is a section on lines III—III of Fig. 1; and Fig. 4 is an end 15 view partly in section on lines IV—IV of Fig. 1.

My invention relates to friction draft rigging and is especially designed for use upon railroad cars of such construction that the 20 draft rigging must have a minimum vertical depth. At the same time my improved rigging is adequate for absorbing and dissipating to a very high degree the shocks of buffing and draft of the rolling stock now 25 in service on railways and which reduces to a minimum the damaging recoil shocks which are inherent in draft riggings now in use.

Referring to the drawings, 2 indicates the 30 housing having a central casing or chamber 3, preferably of cylindrical shape. The housing 2 has enlarged portions 4, preferably formed integral therewith, which are 35 rectangular in form and the rear one of which is adapted to abut against the draft sill stops 5 which are attached to the draft sills 6 of the car structure. 7 is the usual yoke within which the housing 2 lies, and which is adapted to be bolted to the coupler 40 (not shown). The chamber 3 has a hardened steel bearing surface 8 which is held in the chamber by the plate 9, and bearing against the surface 8 are segmental rings 10. Within these segmental rings 10 are 45 the cone rings 11, which space apart the different sets of segmental rings 10 and bearing against the rear set of segments is the equalizer follower 12. At the forward end of the chamber 3 is the front follower 50 13 having a rearward extension preferably integral therewith, which enters between the outer inclined wedging faces of the foremost set of segments 10. Abutting against this rearwardly extending portion 14 of the 55 front follower 13 is a sleeve 15, against the

rear end of which bears the releasing spring 16. The sleeve 15 has a shoulder 17 which is adapted during the releasing operation to strike against the foremost cone 11.

The spring 16 at its rear end bears against 60 an abutment plate 18 which is adapted to be removed to permit the insertion of the equalizer follower 12. This plate 18 is of such shape that after it has been tipped sidewise and inserted it bears against the 65 rear of the casing at the points 19, and in such position forms the rear bearing for the releasing spring 16.

The equalizer follower 12 has arms 20 20' 70 extending at right angles to the axis of the chamber 3, which arms have apertures therein for the reception of the plungers 21 21' which operate in the supplementary chambers 22 22'. The plungers 21 21' have enlarged heads 23 23' at their forward ends, 75 and are secured at their rear ends to the arms 20 20' by means of the pins 24 24'. Upon the plungers 21 21' are coiled the springs 25 25' which bear at their forward ends against the heads 23 23' and at their 80 rear ends against the rear walls of the supplementary chambers 22 22'.

The operation of the draft rigging is as follows: When the coupler receives a buffing shock, this shock is transmitted through the 85 front follower 13 which is caused to move rearwardly, driving its rearward extension back into the casing 2, the rear end of the casing being held from rearward movement relative to the car by the rear draft sill 90 stops 5 which are attached to the draft sills 6. The follower 13 transmits its pressure by a wedging action to the foremost set of segments 10, and this pressure is transmitted from one to the other throughout 95 the entire series of cones and segmental rings, and the entire series is caused to move rearwardly within the casing as the front follower 13 enters the forward end of the casing, carrying with it the equalizer follower 12, the rearward movement of which is resisted by the springs 25 25', which bear 100 forwardly against the heads 23 23', and this resistance is transmitted through the equalizer follower 12 to the rearmost set of 105 segments and to the cones and the other sets of segments, causing a powerful frictional engagement between the exterior surface of the segmental rings 10 and entire cylindrical 110 surface 8 of the casing, thus exhausting the

force of the buffing shock. This frictional engagement of the segments and the interior surface of the casing increases progressively, since as the cones and the segments move 5 rearwardly in the casing the springs 25 25' bear with increasing pressure on the heads, and this pressure is transmitted through the equalizer to the various frictional members as described. When the rigging is under 10 draft, the shock is transmitted to the yoke 7, causing it and the housing 2 to move forwardly as the front follower 13 is held against forward movement by the forward draft sill 5'. The forward action of the 15 casing is resisted by the springs 25 25', which force into wedging engagement through the equalizer follower 12 the cones and segments, causing the same relative movement and progressively increasing frictional engagement between the segments 20 and the casing as when the draft rigging is under a buffing shock. After buffing or draft, the releasing action of the spring 16 drives the sleeve 15 forward and with it the 25 front follower 13, thus releasing the wedging engagement between the follower and the foremost segmental ring. The shoulder 17 then strikes the foremost cone and releases it from wedging engagement with the 30 set of segments immediately to the rear. As the greatest amount of pressure is exerted in the forward part of the casing, it is not necessary to positively release the wedging engagement between the cones and 35 segments further to the rear, since they will automatically release themselves when the wedging engagement of the foremost cones and segments has been relieved.

It is obvious by this construction that 40 not only an efficient and serviceable rigging is provided, but also a device is obtained occupying a minimum of space.

Many variations may be made in the form 45 of rigging as I have described and shown it herein without departing from my invention, since

What I claim is:

1. In frictional shock absorbing mechanism, a member having a longitudinally extending friction surface, sets of coacting friction shoes adapted to be wedged against said friction surface, wedges interposed between adjacent sets of friction shoes, said wedges and sets of shoes being arranged 50 alternately and in tandem, compression springs arranged parallel to the longitudinally extending friction surface and externally thereto, and means for transmitting the pressure of said springs to the shoes 55 and wedges, said means comprising plunger members and an equalizer.

2. In frictional shock absorbing mechanism, a casing, sets of friction shoes and wedges arranged alternately and in tandem 60 within said casing, an equalizer member

adapted to transmit pressure to said wedges and shoes, supplementary longitudinally extending chambers within the casing, springs within the chambers, and plunger members connected at one end to said equalizer, and having abutments at their other ends bearing against said springs. 70

3. In frictional shock absorbing mechanism, a casing having a plurality of longitudinally extending chambers, wedges and sets of friction shoes, arranged alternately and in tandem within one of said chambers, springs located in the other chambers, an equalizer arranged in tandem with the wedges and sets of shoes, and plunger members operatively connecting the equalizer and said springs. 75

4. In frictional shock absorbing mechanism, a longitudinally extending friction member, frictional parts bearing against said friction member, comprising alternately arranged wedges, and sets of shoes, springs arranged externally of said friction member and extending parallel thereto, and an equalizer member and plunger members 80 coacting therewith and adapted to transmit pressure from the springs to the frictional parts. 85

5. In a draft gear, a friction chamber, friction mechanism and springs therein, 90 springs without said chamber, and means connecting said last mentioned springs with the friction mechanism, whereby said last mentioned springs assist to absorb buffing and draft strains transmitted to the friction 95 mechanism, and also serve as a positive releasing means to return the friction mechanism to normal position when the strain is removed. 100

6. In a draft gear, in combination, a friction chamber and spring chambers at the sides thereof, friction mechanism and spring members within the friction chamber, springs within the spring chambers, and means connecting the same with the friction 105 members. 110

7. In a draft gear, in combination, a friction chamber, spring chambers at the sides thereof, and substantially coextensive therewith, friction mechanism within the friction chamber, springs within the spring chambers, and means connecting the friction mechanism and the springs, said means being adapted to draw on the springs rearwardly in buffing movement of the gear. 115 120

8. In a draft gear, in combination, a friction chamber open at both ends, spring chambers adjacent thereto and substantially coextensive therewith, friction mechanism within the friction chamber, springs within 125 said spring chambers, means connecting the friction mechanism and the said springs, said means being adapted to pull rearwardly on said springs in movement of the gear. 130

9. In a draft gear, in combination, a friction chamber open at both ends, spring chambers adjacent thereto and substantially coextensive therewith, friction mechanism within the friction chamber, springs within said spring chambers, means connecting the friction mechanism and the said springs, said means being extended within the friction chamber and adapted to pull rearwardly on said springs on movement of the gear.
10. In a draft gear, a shell, a central friction chamber, and adjacent substantially coextensive spring chambers in said shell, friction mechanism within the friction chamber, shoulders at the rear of the spring chambers, movable spring seats within the spring chambers, and springs between the movable seats and said shoulders, means connecting said spring seats and the friction mechanism, said means being adapted to pull rearwardly on said movable spring seats on movement of the gear.
- 15 friction mechanism within the friction chamber, shoulders at the rear of the spring chambers, movable spring seats within the spring chambers, and springs between the movable seats and said shoulders, means connecting said spring seats and the friction mechanism, said means being adapted to pull rearwardly on said movable spring seats on movement of the gear.
